UNITED STATES PATENT OFFICE.

GARABED ARAMIAN, OF PHILADELPHIA, PENNSYLVANIA.

TOY WHISTLE.

Application filed January 18, 1923. Serial No. 613,382.

To all whom it may concern:

Be it known that I, GARABED ARAMIAN, a citizen of Turkey, having declared my intention to become a citizen of the United States 5 of America, residing at Philadelphia, in the county of Philadelphia and State of Pennsylvania, have invented certain new and useful Improvements in Toy Whistles, of which the following is a specification.

10 This invention relates to certain new and useful improvements in toy whistles wherein the main body portion thereof is constructed in simulation of a vase or pitcher having a laterally directed spout to which a mouth 15 piece is attached.

The primary object of the invention is to provide a toy whistle of the type above described wherein the main body portion and spout are adapted to contain fluid, such as 20 water to produce a warbling effect upon blowing through the mouth piece and spout.

A further object of the invention is to provide a V-shaped notch in the outer end of the upper wall of the spout, the area of which 25 may be varied by adjusting the mouth piece for changing the pitch or tone of the whistle.

With the above general objects in view and others that will appear as the nature of the invention is better understood, the same 30 consists of the novel form, combination and arrangement of parts hereinafter more fully described, shown in the accompanying drawing and claimed.

In the drawing, wherein like reference 35 characters designate corresponding parts throughout the several views,

Figure 1 is a side elevational view, partly broken away and shown in section of a toy whistle constructed in accordance with the 40 present invention, the same being in the general form of a vase or pitcher having a side spout and mouth piece.

Figure 2 is a vertical sectional view of the toy whistle showing water therein to produce a warbling effect,

Figure 3 is a top plan view showing the V-shaped notch in the upper side of the spout with the mouth piece illustrated by dotted lines in a shifted position, and

Figure 4 is a perspective view of the 50 mouth piece.

Referring more in detail to the accompanying drawing, there is illustrated a toy 55 whistle constructed in the form of a vase or pitcher embodying a body 1 having a spaced portion 2 and an outwardly flaring filling upper end 3. A lifting handle 4 is carried by the neck portion of the body.

A side spout 5 projects laterally of the 60 neck portion of the body diametrically opposite the handle 4 as illustrated, the spout 5 being rectangular in cross-section and open at its outer end with the outer end of the upper wall of the spout provided with a V-shaped notch 6 as clearly shown in Fig. 3. 65

A mouth piece 7 of the form best illustrated in Fig. 4 carries a depending flange 8 upon one end thereof, the flanged end of the mouth piece 7 being inserted in the open outer end of the spout 5 as shown in Fig. 2, 70 and if desired may be permanently mounted as by soldering or otherwise. It is also intended that the mouth piece 7 be adjustable in the outer end of the spout 5 as shown in Fig. 3, such adjustability varying the area 75 of the V-shaped notch 6 for changing the pitch or tone of the whistle. Fluid, such as water, indicated by the reference numeral 9 in Fig. 2 is placed in the body 1 of the whistle, the upper level of which is in the 80 neck portion of the body and also in the laterally positioned spout 5 as shown in Fig. 2.

The whistle is operated in the usual manner by placing the mouth piece 7 in the 85 mouth of the user who blows therethrough and the presence of water in the body and spout will cause a warbling effect similar to the songs of certain birds. The pitch or tone of the whistle may be varied by adjusting the mouth piece 7 in the spout 5 for 90 varying the size of the V-shaped notch or opening 6 as shown in Fig. 3. The device is also serviceable as a receptacle for holding cut flowers, and may further be used as 95 a pitcher for containing and pouring fluid, or as an ornamental vase.

While there is herein shown and described

the preferred embodiment of the present invention, it is nevertheless to be understood that minor changes may be made therein without departing from the spirit and scope 5 of the invention as claimed.

What is claimed as new is:

In a toy whistle, a body receptacle adapted to contain fluid, a spout projecting from one side thereof, a mouth piece slidably mounted

in the outer end of the spout, the upper wall 10 of the mouth piece having a V-shaped notch at the outer end thereof, the area of which is varied by the mouth piece, and a depending flange carried by the inner end of the mouth piece engaging the bottom wall of 15 the nozzle.

In testimony whereof I affix my signature.
GARABED ARAMIAN.
